ATTORNEY

UNITED STATES PATENT OFFICE.

GEORGE W. SLADE, OF BALTIMORE, MARYLAND.

RAILROAD TIE.

Application filed January 29, 1924. Serial No. 689,329.

To all whom it may concern:

Be it known that I, GEORGE W. SLADE, a citizen of the United States, residing at 4002 Hawthorne Ave., Baltimore city, in 5 the county of Baltimore City and State of Maryland, have invented new and useful Improvements in Railroad Ties, of which the following is a specification.

My present invention has reference to ties 10 for railway rails.

My primary object is to produce a composition tie of a nature which renders the same strong and durable and which is provided with means for effectively securing the 15 rails thereon.

It is a further object to produce a steel tie reinforced by a concrete body, and which includes plates on which the rails rest, continuous longitudinal reinforcing rods passing through and connected with the plates, other longitudinal reinforcing rods having upset ends terminating in hooks that are received in depressions in the ends of the concrete body, and whereby gripping surfaces 25 are provided which materially assist in the handling of the tie, while means of a novel nature clamp the rails on the rail plates.

With the above broadly stated objects in view and others which will appear as the 30 nature of the invention is better understood, reference is to be had to the drawing which accompanies and which forms part of this application.

In the drawing:—

Figure 1 is a side elevation of a tie in accordance with this invention, the rails being clamped thereon, and parts being in section.

Figure 2 is an end view thereof.

Figure 3 is a sectional view on the line 40 3—3 of Figure 1.

Figure 4 is a sectional view on the line 4—4 of Figure 1.

Figure 5 is a sectional view on the line 45 5—5 of Figure 2.

Figure 6 is a top plan view of one of the rail plates.

Figure 7 is a perspective view of one of the wedges.

Figure 8 is a similar view of one of the 50 rail clamps.

Figure 9 is a transverse sectional view taken through the shank of the clamp.

Figure 10 is a transverse sectional view 55 through the mold box in which the reinforcing concrete body is molded around the metal portions of the tie.

The concrete body of the tie is indicated by the numeral 1. Embedded in the upper face, adjacent to the ends of the body, in the process of molding, there are transversely arranged rail plates 2. Each of the rail plates, adjacent its edges, is formed on its upper face with longitudinal slots or channels 3, and the under face of the plates, below the channels is formed with reinforcing ribs 4. The plates 2, at suitable distance inward of their ends, are provided with transversely arranged openings 5, the inner walls of which being rounded. Below these openings there are welded or otherwise secured on the under face of the plates metal pockets 6. The pocket members may be of thin and comparatively cheap metal, but the rail plates 2 are of steel.

Received in the grooves or channels 3 of the plates 2 there are portions 7 formed by upsetting the upper members 8 of a continuous reinforcing rod. The reinforcing rods are of a substantially rectangular formation, the lower portions 9 being suitably spaced from the upper portions 8, and the connecting ends thereof are curved, as indicated by the numeral 10. As the continuous reinforcing rod is of a length almost equaling that of the body of the tie, and as the said rods are disposed in spaced relation to each other adjacent to the sides of the tie, the same not only provide an ample anchor for the rail plates 2, but afford an effective reinforcement for the concrete body. In addition to the continuous reinforcing rods there are arranged therebelow, and outwardly therefrom, other reinforcing rods 11. These rods have their ends upset, as at 12, and their extremities curved to provide hooks 13. The ends of the tie, in a line with the hooks, are formed with transverse rounded depressions 14. This construction provides a hand grip whereby the ties may be easily handled. The ends 12 of the rods 11 are disposed in close proximity to the outer ends of the concrete body 1 to protect said ends while the hooks are exposed through the depressions 14 and being connected together, as at 15' (Figures 5 and 10), a metal frame is afforded the depressed portions of the body, preventing the breakage thereof.

The openings 5 in the rail plates are spaced away from each other a sufficient distance to receive the rails 15 therebetween. The rails are engaged by the upper headed

ends 16 of clamps 17. Each of the clamps has a depending shank 18 that terminates in a laterally extending hook 19. The outer portion of the shank is rounded as is one of the corners thereof, as clearly disclosed in Figure 9 of the drawings. This permits of the hook 9 being inserted through the openings 5 and the shank 18 turned to bring the jaw 16 over the base flanges of the rails, the rounded portion of the shank contacting with the inner rounded walls provided by the openings 5. The jaws 16 are notched, as at 20, in a line with the outer flat faces of the shanks, and received through this notch 15 for frictional engagement with the straight side of the shank and with the straight walls provided by the openings 5, there are wedge members 21. Each of the wedge members has an offset head 22 that is normally positioned above the tie plates 2, so that an implement, such as a bar, may be inserted therebeneath to remove the wedge. The jaw has its edge, opposite that provided with the notch, formed, on its lower corner with a 25 longitudinal groove 24.

The manner in which the construction is molded is illustrated in Figure 10 of the drawings. It will be noted that the plates 2 are arranged upon the bottom of the mold

and that the reinforcing rods are held in proper spaced relation by wire elements 25. It will be noted that the wire elements are offset at the portions thereof that rest on the inner continuous reinforcing rods and likewise offset to underlie and support the outer and what may be also called the continuous reinforcing rods. The plastic concrete is poured in the mold, and as the mold box has its sections removably connected, the tie may be easily removed therefrom when the plastic body is hardened.

Having described the invention, I claim:—

A railway tie comprising a plastic body, rail plates embedded in the top thereof, a continuous reinforcing rod having rounded corners and offset portions which pass over the plates and which are secured thereto, the rod being embedded in a concrete body, other reinforcing rods disposed below and outwardly of the first mentioned rod, the last mentioned rods having upset ends terminating in hooks which are connected together and the ends of the tie at the hook portions of the rod having transverse depressions therein.

In testimony whereof I affix my signature.

GEORGE W. SLADE.
